UNITED STATES PATENT OFFICE.

JULIUS BUTTERMILCH, OF BERLIN, GERMANY.

ROLLER-SKATE.

SPECIFICATION forming part of Letters Patent No. 584,089, dated June 8, 1897.

Application filed July 23, 1896. Serial No. 600,272. (No model.)

To all whom it may concern:

Be it known that I, JULIUS BUTTERMILCH, merchant, a subject of the German Emperor, residing at Berlin, in the German Empire, have invented certain new and useful Improvements in Roller-Skates, of which the following is a specification.

The present invention relates especially to an innovation in such roller-skates which have two rollers in a line along the center of the skate.

Figure 1 of annexed drawings shows a side view of a complete roller-skate. Figs. 2, 3, 4, 6, and 7 show the attachment of the roller-holders to the foot-plate, in which, according to Figs. 2, 3, and 4, an elastic cushion is used between the roller-holder and the foot-plate. This is lacking in Figs. 6 and 7. Figs. 5, 8, and 4 are intended to explain the front roller-holder, which revolves on a vertical pivot fixed to the foot-plate and which can be fixed rigidly from the side of the same. This mobility is limited by means of striking-pegs.

The foot-plate *a*, Fig. 1, which is fixed to the sole and heel of the shoe by means of a thumb-screw *f* and clamp device *d* *d'* *d''* *e*, is provided at the front and at the back with roller-holders *b* *h*. As the hind roller is rigid, one can, in using an elastic cushion *k*, Fig. 2, attach the same between the foot-plate *d* and the roller-holder *h*, while the roller-holder *h* can be attached by means of the bolts *i* to the foot-plate *d* in such a manner that the surface of the roller-holder *h* can yield on all sides to the pressure of the roller.

In using an elastic cushion *k*, Figs. 3 and 4, for the front roller-holders *b* the lower surface of the roller-holder is covered by a metal plate *b'*, and this metal plate *b'*, as well as the cushion *K*, is attached movably to the foot-plate *a* by means of the bolt *i*. A pivot *r*, Fig. 3, which is attached to the foot-plate *a* and which passes through the cushion *k*, as well as through the plate *b'*, carries on its lower end an adjustable roller-holder *b*.

For the purpose of limiting the rotation the roller-holder is provided on both sides

with a peg *n*, Figs. 4 and 8, and the plate *b'* has on both sides two striking-pegs, so that the roller-holder *b* with the peg *n* can only turn to the right or left round the pivot *r*, Fig. 3, between the pegs *m* *m*, Fig. 5.

To obtain for fancy skates the intended mobility of the front roller-holder *b* and, on the other hand, make the front roller-holder rigid for beginners, the roller-holder *b*, Fig. 7, is screwed fast to the plate *b'* and to the foot-plate *a* by means of the screws *y'*, which pass through the holes *y*, Figs. 3 and 6. The roller *c* or *g* has an elastic tire attached to a hub *S*, Fig. 3. This hub has in the center an oil-cup *v*, so that the balls, which by the inward pressure of the ball-bearing halves *t* are maintained in the hub *S*, are constantly in contact with the oil contained in the oil-cup *v*.

As is shown by Fig. 3, the ball-bearing halves *t* can be provided with a cap *p*, which covers the neck of the hub *S*, thus preventing the dust from entering into the ball-bearings or into the oil-cup. The elastic tire of the roller *c* *g* is made, as seen in Fig. 3, of rubber, and which is placed over the V-shaped groove of the hub.

I claim—

In combination, the foot-plate, the pivot-stud extending down therefrom, a wheel-bracket pivoted on said stud and having lateral extensions, the plate *b'* between the wheel-bracket and the foot-plate, the stops between the adjacent faces of the plate *b'* and the wheel-bracket, said plate *b'* having portions which together with the lateral extensions of the bracket are perforated so that by bringing said perforations into alignment the wheel-brackets may be rigidly fixed by a screw or pin, substantially as described.

In witness whereof I have hereunto signed my name in the presence of two subscribing witnesses.

JULIUS BUTTERMILCH.
